WEDGE FASTENED CABINET HINGE

Leslie Niels Hansen, Hurricane, Utah

Application August 3, 1956, Serial No. 602,022

2 Claims. (Cl. 16—159)

This invention is the result of a search for a semi-concealed hinge that would lend itself to mass production methods, where a large number of identical parts are made with machine accuracy. It was desirable that the hinge fit into a machine made opening to minimize the human error and at the same time permit simple, fast assembly. These objectives are met in the invention set forth in the following specification:

Referring to the drawing: Figure 1 is a multiple view drawing in which Figure 1A is an end view of the hinge looking toward the right in Figure 1B; Figure 1B is a top plan view of the hinge; Figure 1C is a side elevational view of the hinge showing some of the parts in different positions by broken lines.

Figure 2 is a perspective view of the hinge and a portion of a cabinet door illustrating how the hinge is mounted on the door.

Figure 3 is a side elevational view of the hinge mounted on the cabinet and door with the cabinet and door shown in section and with parts broken away.

As shown in the drawing one leaf of the hinge, indicated by the numeral 1, is of conventional construction adapted to be attached to a cabinet stile 8 by any suitable means. Hinge leaf 1 is connected by the pivot pin 2 to a second leaf 3, the latter comprising two identical parts separated by a wedge 4 of the same shape but shorter than the identical parts. Wedge 4 is pivoted at 5 between the identical parts as clearly shown in Figs. 1C and 2. The leaf 3 is also provided with a plurality of

2

deformities or dimples 6 for a purpose to be explained hereinafter.

Installation is made by setting up a circular saw of proper diameter, so that it will cut almost, but not quite through to the face of the door 7, with a stop so that the kerf is cut only to the point where the inner edge 9 of the door is at the center line of the saw. After the kerfs have been cut in the door, the hinge with the wedge in the open position, is forced into place and the wedge 10 driven shut, wedging the hinge securely in place. The deformities or dimples 6 add gripping power.

I hereby claim and request Letters Patent on the following device:

- 15 1. A hinge, one leaf of which is comprised of three parts, two of which are identical in shape and size to fit the kerf of a circular saw cut normal to the hinge edge of a cabinet door; said identical parts being adapted to extend almost through, but not to the face of said door; 20 the third part being similar in shape but shorter than the two identical parts, and being therefor pivoted between them on a retaining pin, and being of such thickness that when forced between the identical parts which have been fitted and held in the saw cut, locks them snugly in place.
- 25 2. A hinge, one leaf of which is comprised of three parts, two of which are identical in shape and size to fit the kerf of a circular saw cut normal to the hinge edge of a cabinet door, said identical parts being adapted to extend almost through but not to the face of said door, and the identical parts being dimpled or deformed along the circular edge to afford better holding power, the third part, which is similar in shape but shorter than the identical parts being pivoted between them on a retaining 30 pin, and being of such thickness that when forced between the identical parts, which have been fitted and held in the saw cut, locks them securely and permanently in place.
